UNITED STATES PATENT OFFICE.

HENRY W. GILBERT AND EVA MAYNARD MARTIN, OF MEADVILLE, PENNSYLVANIA,
ASSIGNORS TO THE SPIRELLA COMPANY, OF MEADVILLE, PENNSYLVANIA, A COR-
PORATION OF PENNSYLVANIA.

CORSET.

956,957.

Specification of Letters Patent.

Patented May 3, 1910.

Application filed May 2, 1908. Serial No. 430,497.

To all whom it may concern:

Be it known that we, HENRY W. GILBERT and EVA MAYNARD MARTIN, citizens of the United States, and residents of Meadville, 5 in the county of Crawford, in the State of Pennsylvania, have invented new and useful Improvements in Corsets, of which the following, taken in connection with the accompanying drawings, is a full, clear, and 10 exact description.

This invention consists in a novel construction of a corset designed to afford great convenience to the wearer of the corset and permit ample physical exercise essential to 15 promote the health of the person and also produce dress-improvement of the person.

Figure 1 is a detached plan view of a corset embodying our invention; Fig. 2 is an enlarged transverse section on the line 20 —X—X— in Fig. 1; Fig. 3 is an enlarged fragmentary face view of one of the corset-sections showing one of the forms of the variously curved wire-stays adapted to be used in our improved corset; and, Figs. 4 25 and 5 show the corset applied to a person and illustrating the effects of the corset.

The fabric body of the corset is composed of a back-section —A— and two front sections —B—B—. The back section —A— 30 is formed with side extensions —A¹—A¹— and the front sections —B—B— are extended to the said side extensions and are adjustably connected thereto by means of elastic lacings —a— which pass through eye- 35 lets —b— between the hemmed edges —c—, and stays disposed in pockets —c¹— formed in the fabric body.

The front edges of the front portions —B—B— are each provided with two parallel hems as shown at —d—d— and one of said sections is provided with button-holes —e— between the two hems. The front edge of the other section —B— is provided with a corset-stay disposed in a pocket 45 —f— between the two hems —d—d—. This latter section has a series of tape loops —f¹— attached to the hem —d— farthest from the edge of the said section, and to these loops are attached buttons —f²—f²— 50 adapted to pass through the button-holes —e— in the operation of donning and removing the corset onto and from the person. The stay in the pocket —f— imparts the desired vertical stiffness to that portion 55 of the corset, while the button-carrying loops

—f¹— attached to the fabric body separate from the aforesaid stay, affords an elastic connection of the two front sections —B—B—. To further increase the circumferential elasticity of the corset we employ corset stays composed of spring wire —1— curved successively into a series of loops —2— which are disposed transversely in relation to the pockets —3— into which said stays are inserted. These pockets extend curvilinearly from the top to the bottom of the corset and the said wire-stays readily conform to the said curvilinear arrangement of the pockets and permit universal flexure of the corset without causing wrinkling of 60 the fabric-body thereof.

We do not limit ourselves to any specific form of the curved wire —1— as this feature admits of many modifications. The essential feature of the said wire stay is in its 65 ability of being flexed in any direction without danger of being broken.

The top edge of the said corset is formed with increased downward curvature as shown at —h— at the underarm portions of 70 the corset for the purpose of rendering the corset convenient to the wearer when practicing athletic exercises.

—i—i— denote shoulder straps which are tapered from their permanent attaching ends 75 partway toward the free ends thereof. Said attaching ends are formed with wide transverse edges which are sewed to the top edge of the back section —A—, from whence the said straps extend across the adjacent shoulders 80 of the wearer as shown in Figs. 4 and 5 of the drawings and are pinned or otherwise adjustably connected to the top portions of the front sections —B—B—. Said shoulder straps are curved longitudinally and the attachment of the wide ends thereof to the top edge of the back section —A— causes them to be maintained flat, comfortable, and secure on the shoulders of the wearer.

—t—t— represent buttons for attaching 90 the waist-band of a garment. These buttons are attached to tape loops —n— attached to the fabric body adjacent to the stay-pockets —3—. Said buttons are thus securely retained on the corset and conveniently manipulated in connecting the aforesaid waist-band to the corset.

What we claim as our invention is:
A corset consisting of a fabric body composed of a back section and two front sec- 105

tions, and having its top edges formed with increased downward curvatures at the underarm portions, the said back section formed with side extensions, the rear edge 5 portions of the front sections and adjacent edge portions of the extensions being hemmed and formed thereat with pockets, stays consisting of looped wire disposed in the pockets, eyelets fastened to the said front 10 sections and extensions and arranged between the hemmed edges and stays, elastic lacings passing through the eyelets for adjustably and yieldingly connecting said front sections and extensions, the front edges of 15 the front sections each provided with two parallel hems and one of the said front sections provided with button-holes between the two hems, the front edge of the other front sections provided with a pocket between its two hems, a wire stay disposed in 20 said pocket, a series of tape loops attached to the latter section at the hem farthest from

the edge thereof, buttons secured to said loops and arranged correspondingly with the aforesaid button-holes, shoulder-straps sewed to the top edge of the back section, said straps being tapered from their permanently attached ends partway toward their free ends and curved longitudinally and formed with wide transverse attaching edges to 25 maintain them flat and secure on the shoulders of the wearer, the free ends of the straps being detachably and adjustably connected to the top portions of the aforesaid front sections, and waist-band attaching 30 means consisting of a series of tape loops 35 fastened to the corset body adjacent to the stay-pockets and provided with buttons as set forth and shown.
